Attorney.

UNITED STATES PATENT OFFICE.

DAVID T. PARKINSON, OF WICHITA, KANSAS.

APPARATUS FOR THE MANUFACTURE OF DENTAL CROWNS.

1,304,087.

Specification of Letters Patent. Patented May 20, 1919.

Application filed July 8, 1916. Serial No. 108,230.

To all whom it may concern:

Be it known that I, DAVID T. PARKINSON, a citizen of the United States, and resident of Wichita, county of Sedgwick, and State 5 of Kansas, have invented an Improvement in Apparatus for the Manufacture of Dental Crowns, of which the following description, in connection with the accompanying drawings, is a specification, like letters on the 10 drawings representing like parts.

My present invention is an improvement in the manufacture of tooth crowns from blanks, and comprises means for use in crowning teeth and the object of the invention 15 is to improve, simplify and perfect the same.

Heretofore it has been customary, in the manufacture of dental crowns from blanks, to use a die, or a series of dies for the different 20 teeth, made according to the standard measurements scientifically established, such dies being in two parts so as to permit the die being opened after the crowned part of the blank has been swaged outwardly;—or 25 the dies have been of lead or similar material which had to be cut open after the crown was completed. As practically all such crowns were of less diameter at the root-engaging portion than at the top or crown, 30 it was, of course, impossible to have a closely fitting die without opening it to extract the finished crown, either by cutting it open, or by having the same in two parts. Such prior systems were unsatisfactory, being 35 slow and expensive, particularly where a special die was cast for each tooth and then cut open, as well as in using a two-part die which was apt to mar the crown, form ridges at the seams, and the like. A further difficulty 40 with the use of prior dies has been that a different die was requisite for tooth crowns of different neck diameters, *i. e.*, where the crown fitted upon the root, and this necessitated a very large number of separate 45 dies, and therefore it was often preferable to melt, mold and cast a particular die of lead or other material for each tooth crown to be made. My invention obviates all these prior difficulties, cumbersome methods, two-part dies, or specially molded dies, and enables a permanent metal die to be used, irrespective of the diameter of the neck of the 50 crown blank and always enables the completed crown to be readily removed from the die without injury, and yet to produce a seamless crown quickly and perfectly.

It will be understood that the saving in time in manufacturing metal tooth crowns is also of great importance, and by means of my invention a crown blank can be quickly 60 and almost immediately swaged out of a tubular blank of gold, platinum, silver, or the like, or any suitable metal or alloy, giving the proper contour and occluding surface to the completed crown, irrespective of the 65 diameter of the neck of the crown or tooth root to which it is to be affixed. In carrying out my invention, a set of single-part, solid metal dies is provided with suitable contour for each different tooth, and a set 70 of tubular blanks, having the proper diameter for the neck of the crown to fit upon the circumference of the tooth root at the gum line. Having then prepared the real root, the measurement of its diameter is 75 taken and a blank of corresponding diameter selected. Such blank is then applied to the die having the particular occluding surface contour for the tooth to be crowned, and the lower portion of the blank partially filled 80 with shot or other suitable expansible material. A plunger of proper diameter to fit the neck of the blank is then utilized, and the crown portion flared outwardly and swaged to the tooth form in the bottom of 85 the die, by the application of pressure, through a hammer or press, upon the plunger. I have discovered that this swaging method will not enlarge the original diameter of the blank at the neck portion, where 90 a small amount of shot is employed, just sufficient to swage out the crown of the blank, and therefore the die is formed with its top or mouth open, of suitable diameter to permit the withdrawal of the completed flared 95 crown portion. Thus a solid die may be formed without any undercuts or the like, and may have the sides diverging from the bottom upwardly toward the top or mouth, permitting the removal of the completed 100 crown and also permitting the crown swaging of metal blanks of different diameters.

A further feature of importance is the fact that a perfectly fitting crown is always produced, the measurement of the diameter of the 105 tooth root determining the size blank to be used, which blank is of just the right diameter to fit thereon at the gum line, and the swaging does not mar or alter this diameter at the neck of the crown. In the accompanying drawing a simple form is illustrated, 110 showing the process and apparatus for shap-

ing a single tooth, but it will be understood that a corresponding die for each tooth will be employed, and blanks of proper diameter provided as above explained. It being a 5 well-known fact that natural teeth are formed after certain typical contours, which forms vary but little except in size, my system and process are peculiarly adapted for the manufacture of different-diametered 10 seamless crowns in the same die.

Referring to the drawings, illustrating a preferred embodiment of my invention,

Figure 1 is a view, in perspective, of a tubular blank;

15 Fig. 2 is a view of my novel form of solid die;

Fig. 3 is a cross-sectional view through the die and a blank preparatory to swaging;

Fig. 4 is a completely swaged tooth;

20 Fig. 5 is a view of a plunger of suitable diameter to slidingly fit the particular blank to be used therewith; and

Fig. 6 is a cross sectional view through the die and blank after the latter has been 25 swaged to convenient contour.

For the purpose of illustration, I have shown in the drawings a single die, blank and plunger, to elucidate the process of making a crown for an upper first molar. 30 As above noted, my invention contemplates the provision of an entire set of dies, and of different-diametered blanks and plungers or swaging tools for each diameter of blank to be employed. Also, these dies may be

35 fitted in a table, and adapted to be brought into proper position under the hammer of a swaging press or the like. In carrying out my process, a metallic die 1, having its inner or bottom surface 2 of suitable contour for 40 the particular molar in which the crown is provided, the die opening being flared or divergent as indicated at 3 toward the top 4 so that a crown may be readily lifted out after it has been swaged to the diameter 45 permitted by the contour 2. A tubular blank 5 is then selected having its diameter of proper dimensions to fit the tooth which has been measured and for which the crown is to be made. Such blank is positioned with-

50 in the die 1, and may be held by pliers, by hand, or otherwise, and a quantity of shot or the like 6 is put in the bottom. Then a plunger 7 of corresponding diameter to that of the blank 5 is selected and applications of 55 pressure imparted thereto by a hammer or by

a machine, which rapidly swages out the crown 8 of the blank as illustrated in Figs. 4 and 6. The plunger may be then removed and the completed crown lifted out of the die 1, the flaring mouth or opening 3 permitting such removal. The die can be used repeatedly and irrespective of the diameter of blank 5 to be swaged therein, and therefore a large range of different-sized crowns can be formed in one die, providing all are 60 for the same relative teeth. The plunger 7 being of proper diameter to fit the blank, will not distort nor destroy the neck portion of the blank, which will therefore fit the tooth root of similar or appropriate measurement and the entire process of measuring the root, selecting a blank, and swaging the crown, and fitting the completed crown onto the tooth, can be quickly effected by means 70 of my invention. No uneven surfaces in the 75 crown are made as in the case of two-part dies, and no specially molded and cast die need be made which afterward must be cut open and the material remelted and cast for another tooth crown. The entire crown 80 manufacture and fitting can be accomplished during a short time, while the patient waits, if desired, instead of requiring repeated visits and days' intervals. My invention is 85 as feasible in the manufacture of the incisors as in the making of bi-cuspids and molars.

My invention is further described and defined in the form of claim as follows:—

An apparatus for making seamless dental 90 crowns comprising a lower die having a cavity the bottom of which has the intaglio configuration of a crown top, said cavity having an opening at least equal to the largest cross sectional dimension of the finished 95 crown, a plunger adapted to receive blanks for forming the crown, and yielding material arranged in the blank at the end of the plunger, said plunger adapted to coöperate with said lower die whereby said yielding 100 material is forced out and the blank stretched to fit the lower portion of the lower die.

In testimony whereof, I have signed my name to this specification, in the presence of 105 two subscribing witnesses.

DAVID T. PARKINSON.
